(57) **CLAIM**

The ornamental design for a free-standing lamp as shown
and described.

DESCRIPTION

FIG. 1 is a perspective view of a free-standing lamp showing
a first embodiment of our new design;

FIG. 2 is a left side elevational view of the free-standing
lamp of FIG. 1;

FIG. 3 is a right side elevational view of the free-standing
lamp of FIG. 1;

FIG. 4 is a front elevational view of the free-standing lamp
of FIG. 1;

FIG. 5 is a rear elevational view of the free-standing lamp
of FIG. 1;

FIG. 6 is a top plan view of the free-standing lamp of FIG.
1; and

FIG. 7 is a bottom plan view of the free-standing lamp of
FIG. 1.

FIG. 8 is a perspective view of a free-standing lamp showing
a second embodiment of our new design;

FIG. 9 is a left side elevational view of the free-standing
lamp of FIG. 8;

FIG. 10 is a right side elevational view of the free-standing
lamp of FIG. 8;

FIG. 11 is a front elevational view of the free-standing lamp
of FIG. 8;

FIG. 12 is a rear side elevational view of the free-standing
lamp of FIG. 8;

FIG. 13 is a top plan view of the free-standing lamp of FIG.
8; and,

FIG. 14 is a bottom plan view of the free-standing lamp of
FIG. 8.

The broken lines shown in the drawings depict portions of
the free-standing lamp that form no part of the claimed
design.
